UNITED STATES PATENT OFFICE.

WALTER W. TODENWARTH, OF ROSELLE, NEW JERSEY, ASSIGNOR OF ONE-HALF TO CLARENCE E. PRYOR, OF JERSEY CITY, NEW JERSEY.

HYDROCARBON-BURNER.

1,336,798.

Specification of Letters Patent. Patented Apr. 13, 1920.

Application filed May 15, 1919. Serial No. 297,253.

To all whom it may concern:

Be it known that I, WALTER W. TODENWARTH, a citizen of the United States, and residing at Roselle, in the county of Union 5 and State of New Jersey, have invented certain new and useful Improvements in Hydrocarbon-Burners, of which the following is a specification, such as will enable those skilled in the art to which it appertains to 10 make and use the same.

This invention relates to hydrocarbon burners of the class used in stoves, ranges, furnaces and other heaters, and the object thereof is to provide an improved device of 15 this class which is simple in construction, efficient in operation and comparatively inexpensive; a further object being to provide a hydrocarbon burner of the class and for the purpose specified which may be easily controlled and by means of which the 20 highest possible degree of heat in proportion to the fuel consumed may be obtained.

The invention is fully disclosed in the following specification, of which the accompanying drawing forms a part, in which the 25 separate parts of my improvement are designated by suitable reference characters in each of the views, and in which:—

Figure 1 is a sectional side view of my 30 improved burner;

Fig. 2 a plan view on an enlarged scale with part of the construction broken away; and,

Fig. 3 a sectional side view on the same 35 scale as Fig. 2 and at right angles to Fig. 1.

In the practice of my invention as shown in the drawing, I provide a base a which is preferably pan-shaped in form and provided with legs a^2 and in the bottom of 40 which is a longitudinal receptacle a^3 designed to receive any suitable fibrous material to serve as an initial burner.

The base a is also provided centrally thereof and also centrally of the receptacle a^3 with 45 transverse raised supports a^4 , and arranged transversely of the base and integrally therewith is a frame member a^5 having a transverse head portion a^6 provided centrally with a tubular portion or sleeve a^7 .

50 I also employ a burner head b which is circular in form, in the construction shown, and which comprises a main central burner plate b^2 below which are supplemental burner plates b^3 which, in the construction

shown, are three in number, and said supplemental burner plates are of less diameter than the main central burner plate and above the main central burner plate b^2 are supplemental burner plates b^4 which are also three in number, and less in transverse 55 dimensions than the main burner plate b^2 and greater in transverse dimensions in the construction shown than the supplemental burner plates b^3 , and the burner plates b^2 , b^3 and b^4 are connected by vertically arranged rods b^5 .

The burner plates b^3 and b^4 are annular in form and this forms in the burner head a top chamber b^6 and a bottom chamber b^7 , and the central burner plate b^2 is provided 70 with a central port or passage b^8 controlled by a valve b^9 having a threaded stem b^{10} passed through the top burner plate b^4 and provided with a milled head b^{11} .

The burner plates b^2 , b^3 and b^4 , with the 75 exception of the top plate b^4 , are provided on their upper surfaces with small raised knobs or projections b^{12} by which said plates are separated so as to form thin annular burner slits b^{13} , and the top burner plate b^4 is provided with a plurality of circularly 80 arranged apertures b^{14} which also form burners and over which are placed or supported a circular or ring-shaped deflector b^{15} , the bottom burner plate b^3 at the bottom of the burner head b is provided centrally with a tubular sleeve b^{16} , which passes 85 downwardly through the sleeve a^7 of the frame a^5 of the base a , and said sleeve is provided with a set screw c which bears on the sleeve b^{16} , and by means of this construction the burner head b may be adjusted 90 vertically as will be readily understood.

A vapor tube d is arranged longitudinally of the base a on the supports a^4 and provided with a small burner orifice d^2 , and detachable cap d^3 , and said vapor tube d is provided with an upwardly directed supply tube extension d^4 , preferably composed of two parts as shown connected at d^5 , and 100 passing into the base a is an oil or hydrocarbon supply pipe e which passes through coupling members e^2 connected with the base a , and said pipe e is provided with an upwardly directed extension e^3 parallel with the burner supply tube d^4 , and connected therewith by brace members e^5 , any desired 105 number of which may be employed, and

employed in connection with the burner head b is an annular retort tube f , the normal position of which is just above the main central burner head plate b^2 , and said retort tube f is open at one side and the ends of the side portions thereof are connected with the pipes d^4 and e^3 at f^2 .

The retort f and the tubes d^4 and e^3 are, in the construction shown, filled with fine wires or strips f^3 composed of aluminum or other metallic substance, and the object of which is to regulate the flow of the hydrocarbons in gaseous or other forms through said parts and also to aid in heating the hydrocarbon in the retort f .

The operation will be readily understood from the foregoing description when taken in connection with the accompanying drawing and the following statement. It will be understood that the hydrocarbon supply pipe e is provided with the usual control valve, and the position of the parts of the burner shown in Figs. 1 and 3 may be considered as the normal position, and in the use of my improved burner it is set into the fire-box of a stove, range, furnace or other heater and takes the place of other sources of heat such as coal or wood. In starting the burner the valve in the supply pipe e is opened and the oil is allowed to flow through the pipe member e^3 , the retort f , and the pipe member d^4 into the vapor tube d and a small amount of alcohol or a volatile hydrocarbon is placed in the receptacle a^3 to saturate the fibrous material therein, and this fibrous material is ignited and serves to give the vapor tube d an initial heat and to convert the hydrocarbon therein into vapor which is discharged into the sleeve b^6 of the burner head b through which it passes into the chamber d^7 from which it passes out through the annular burner orifices b^{13} and may be ignited, and the flame from the burner orifices b^{13} pass up around the main central burner plate b^2 and around the retort tube f , and said retort tube is highly heated as will be readily understood, and the vapor produced therein is carried to the vapor tube d and discharged into the sleeve b^6 through which it passes back to the burner head and a constant supply of vapor is thus produced and the operation of the burner head will be continuous and automatic.

It will be understood that either the bottom chamber b^7 of the burner head or both said chamber and the top chamber b^6 may be employed by means of the valve b^9 or the manipulation thereof, and when the valve b^9 is open the vapor passes into both of said chambers and out between the burner plates b^3 and the burner plates b^4 , and the flame from the burner orifices b^{13} between the plates b^4 strike the retort tube f directly and said retort tube is highly heated and the vapor produced therein and carried to the

tube d constitutes what may be called a fixed gas, and in this way the highest possible degree of heat may be obtained.

When the top chamber b^6 of the burner head is employed the vapor also passes out through the burner orifices b^{14} of the top plate b^4 and the annular flame thus produced strikes the bottom of the annular deflector b^{15} and said flame is broken up and deflected both inwardly and outwardly over the central portion of the burner head and over the retort f , and this also serves to increase the degree of heat produced and increase the vaporization of the hydrocarbon in the retort f .

It will also be seen that by the vertical adjustment of the burner head herein described, the position of the sleeve b^6 with reference to the vapor tube d and the position of the burner head with reference to the retort f may be adjusted and the operation of the device thus controlled to an extent.

The arrows in Fig. 3 will show the direction of the various flames or flame sheets produced by the burner head under different conditions and the vapor supplied to the burner head may be limited to the bottom chamber b^7 and the flames or flame sheets produced will be directed outwardly beneath the central plate b^2 of the burner head and will serve to heat the retort f only to the degree necessary to supply the burner with vapor, and to produce a moderate degree of heat in the stove, range, or other apparatus in connection with which the burner is employed, or the said burner head may be controlled so as to highly heat the retort or to heat said retort to any desired extent, and in this way a very high degree of heat may be produced.

With my improved burner the entire fire-box of an ordinary stove, range, or similar heater can be filled with flame heated at a very high degree of temperature and the divisional construction of the burner head provides means whereby a part of the capacity of said heat may be employed whenever desired, or the entire capacity thereof when necessary.

I also provide means for keeping the burner orifice d^2 in the burner tube d clean, comprising a rod g mounted horizontally in the base a and provided at its outer end with a head g^2 by which it may be manipulated, and said rod is provided at its inner end with an arm g^3 having at its end a pin g^4 and by turning the rod g the arm g^3 may be thrown into the position shown in Fig. 3, in which operation the pin g^4 will pass into and through the orifice d^2 in the vapor tube d and clean said orifice.

It will also be understood that the size, or capacity of the burner head b may be increased or decreased by increasing or decreasing the number of burner plates b^3 and

b⁴, and said burner head may be of any desired transverse dimensions, and while I have shown and described the preferred construction for carrying my improvement into effect, my invention is not limited to the details of construction herein shown and described, and changes therein and modifications thereof may be made, within the scope of the appended claims, without departing 10 from the spirit of my invention or sacrificing its advantages.

Having fully described my invention, what I claim as new and desire to secure by Letters Patent, is:—

15 1. In a hydrocarbon burner, a burner head having top and bottom chambers which are in communication, means for controlling said communication, and means for supplying vapor to the bottom chamber, said 20 burner head being provided above and below said first named means with a plurality of superimposed plates between which are burner orifices.

25 2. In a hydrocarbon burner, a burner head comprising a main central plate, supplemental plates placed above and below the main central plate and forming in connection therewith top and bottom chambers, the central plate being provided with a port, a 30 valve for controlling said port, and said main central plate and said supplemental plate being provided therebetween with burner orifices.

35 3. In a hydrocarbon burner, a burner head comprising a main central plate, supplemental plates placed above and below the main central plate and forming in connection therewith top and bottom chambers, the central plate being provided with a port, a 40 valve for controlling said port, and said main central plate and said supplemental plate being provided therebetween with burner orifices, and the top supplemental plate being also provided with circularly arranged burner orifices over which is placed 45 an annular deflector.

45 4. In a hydrocarbon burner, a base, and a burner head supported thereover and comprising a main central transverse burner plate having a central port, annular burner plates placed above and below the central plate and between which and the central plate are annular burner orifices, and a valve 50 for controlling the port in the central plate.

55 5. In a hydrocarbon burner, a base, an annular retort above said base and provided with a hydrocarbon supply, a vapor tube in communication with said retort and a burner head vertically adjustable and adapted to 60 receive vapor from said vapor tube, said burner head being divided into separate top and bottom compartments having a plurality of annular discharges and said compartments being provided with a valve controlled 65 communication.

6. A burner of the class described comprising a base, a vapor tube supported in said base, a retort tube in communication with the burner tube, means for supplying fuel to the retort and vapor tubes, a burner head 70 adjustably mounted in the base and adapted to be moved toward and from said retort tube, said burner head being divided into top and bottom chambers, means for supplying vapor to said chambers, and means for discharging the vapor from said chambers through a plurality of annular discharges. 75

7. A burner of the class described comprising a base, a vapor tube supported in said base, a retort tube in communication with 80 the vapor tube, means for supplying fuel to the retort and vapor tubes, a burner head adjustably mounted in the base and adapted to be moved toward and from said retort tube, said burner head being divided into top and 85 bottom chambers placed in communication by a central port or passage, and means for supplying vapor to said chambers, each of said chambers being provided with a plurality of discharge openings through which 90 the vapor in said chambers is adapted to pass.

8. In a hydrocarbon burner, a burner head having top and bottom chambers, means for placing said chambers in communication, 95 and means for supplying vapor to said chambers, said burner head being provided above and below said first named means with a plurality of superimposed plates between which are burner orifices. 100

9. In a hydrocarbon burner, a base provided with a horizontally arranged vapor tube, a vertically adjustable burner head mounted over said tube and provided with a sleeve adapted to receive vapor from said tube, an annularly arranged retort tube inclosing said burner head and in communication with said vapor tube, a supply tube in communication with said retort tube, and said burner head being provided with a plurality of annularly arranged burner orifices divided into top and bottom sections, the top section being of greater dimensions than the bottom section. 105

10. In a hydrocarbon burner, a base, a burner head supported thereover and comprising a main central transverse burner plate having a central port, and a plurality of annular burner plates placed above and below the central plate and between each of 110 said plates and the central plate are burner orifices. 120

11. In a hydrocarbon burner, a base, a vertically adjustable burner head supported over said base and divided into top and bottom chambers, means for supplying vapor to said chambers, and means for discharging vapor from said chambers through a plurality of annular burner orifices. 125

12. A burner of the class described com- 130

prising a base, a vapor tube supported in said base, means in the base for heating said vapor tube, a retort tube in communication with said vapor tube, means for supplying fuel to said retort and vapor tubes, a burner head mounted in the base and comprising a central ported plate, supplemental plates mounted above and below said central plate, said plates being provided therebetween and between said central plate with annular burner orifices, the top supplemental plate being provided with a plurality of upwardly directed and circumferentially arranged

burner orifices, an annular deflector mounted above said last named orifices, and means whereby vapor from said vapor tube may be supplied to and discharged from said orifices.

In testimony that I claim the foregoing as my invention I have signed my name in presence of the subscribing witnesses this 2nd day of May 1919.

WALTER W. TODENWARTH.
